CARBONPROOF PLUG

Hector Rabazzana, Flint, Mich., assignor, by
mesne assignments, to General Motors Corporation, Detroit, Mich., a corporation of Delaware

Application August 6, 1932, Serial No. 627,684

4 Claims. (Cl. 123—169)

This invention relates to ignition equipment for internal combustion engines, and particularly to an improvement in spark plugs.

It is well recognized that the proper and efficient functioning of a spark plug depends largely upon the temperature to which it is subjected during use. If a plug runs too hot pre-ignition troubles will result, and if it runs too cold, carbon or oil will deposit on the plug parts and short circuit the gap. To avoid fouling, the temperature of those portions exposed in the combustion chamber must be high enough to burn away any products of combustion deposited thereon and yet below the point where pre-ignition is likely to occur. For this reason a plug must be designed according to the type of engine it is to be used with and the temperature at which such engine normally operates.

With these things in mind it is here proposed to provide a spark plug especially adapted for a relatively cool running engine and which embodies a heat absorbing portion having a comparatively large surface area exposed to the heat of combustion together with a restricted connection with the main body of the plug. Because of this arrangement, the dissipation or transference of heat taken up by the heat absorbing portion will be retarded and at a rate to store up sufficient heat to maintain the temperature high enough to burn away the carbon and keep the plug clean.

A better understanding of the invention will be had upon reference to the accompanying drawing, wherein, Figure 1 is a side elevation 35 of a spark plug in operative position, in an engine cylinder head, a portion of the head being shown in section. Figure 2 is a vertical sectional view taken on line 2—2 of Figure 1, and Figure 3 is a transverse section taken on line 3—3 of Figure 2.

Referring to the drawing, the reference numeral 1 indicates a water cooled cylinder head of an internal combustion engine, having a combustion chamber 2. Positioned within an opening through the wall of the head 1 is a screw threaded skirt 3 of the outer metal shell 4, which as is usual in spark plug design encloses an insulator core 5 surrounding a central electrode 6.

At the lower end of the skirt and directly exposed to the combustion chamber 2 is a heat absorbing element 7, which as shown in the drawing, may comprise a relatively narrow ring presenting a large surface area to the heat of combustion. This ring is connected to the main body of the plug or skirt 3 by one or more re-

stricted neck portions 8 which afford the only path for the flow of heat absorbed by the ring 7 into the skirt 3, from which the heat is taken up by the head 1 and transferred to the cooling medium in the water jacket. Because of the 60 restricted path of heat flow and of the large surface area exposed to the heat, the temperature of the narrow ring 7 will be maintained at a considerably higher point than that of the remainder of the plug and thereby prevent the 65 accumulation of carbon deposits.

In the manufacture of the plug, the ring 7 may be formed initially as a part of the skirt proper and later separated by a pair of saw kerfs cut inwardly from diametrically opposite 70 points adjacent the inner end of the skirt.

To provide the spark gap, use is made of a side wire or grounded electrode 9 ending in spaced relation to the central electrode 6, and mounted on the underside of the ring 7, preferably in line with one of the neck portions 8. By so mounting the side wire, the heat taken up by it can be readily transferred through the neck and into the main wall of the skirt, so as to obviate harmful effects of too much heat on 80 the side wire.

It will be understood that by varying the size of the heat absorbing element and its connection and relation to the main portion of the plug, the operating temperature thereof may be regulated in accordance with conditions of use. It 85 will also be understood that various modifications may be made of the specific embodiment here referred to.

I claim:

1. A spark plug shell having a pair of saw kerfs cut therein adjacent its inner end from diametrically opposite points and extending throughout the major portion of the shell to afford air space insulation between the end portion and the shell with restricted neck portions therebetween, and a grounded electrode wire mounted on said end portion in alignment with one of said neck portions. 90

2. A spark plug shell having a pair of transverse saw kerfs cut from opposite sides thereof immediately adjacent its inner end to afford a narrow heat storing ring in axial alignment and integral with the main body of the shell, said saw kerfs being so related as to leave a bridge 105 connecting said ring and main body of the shell and providing therebetween a restricted heat flow path. 100

3. A spark plug shell having immediately adjacent its inner end a saw kerf cut transversely 110

throughout a relatively large portion of its circumference to afford a relatively narrow end portion in axial alignment with the main body of the shell and leave a restricted neck between 5 said end portion and the main shell body for the flow of heat.

4. A spark plug shell having portions thereof removed on a line extending transversely of the

shell axis and immediately adjacent the inner end thereof to afford an opening through the wall thereof throughout a major part of its circumferential extent for breaking the heat flow path between the endmost portion and the main body of the shell. 80
